Application May 19, 1944, Serial No. 536,315

8 Claims. (Cl. 15—57)

1

This invention relates to a barrel washer and has for one of its objects the provision of a washer adapted to more efficiently clean the outsides of barrels than heretofore.

Another object of the invention is the provision of an automatic barrel washer that is adapted to scrub the ends and sides of barrels for a predetermined length of time sufficient to insure a thorough cleaning thereof and to remove each barrel so washed while admitting another barrel to the scrubbing process as soon as the previously washed barrel is removed. The ejection or removal of the washed barrel and the admission of a barrel to take the place in the scrubbing compartment of the removed barrel are automatically performed so that all an operator is required to do is to feed the barrels to a delivery line that communicates with the scrubber and delivers the barrels to the latter at the proper time.

Other objects and advantages will appear in the drawings and in the description.

In the drawings Fig. 1 is a semi-diagrammatic view of the scrubber and control system therefor.

Fig. 2 is a plan view of the scrubber, the delivery and discharge conveyors from the wash and rinse compartments at opposite sides thereof being only partially shown.

Fig. 3 is a side elevational view of the scrubber from one side thereof, the delivery and discharge conveyors from the wash and rinse compartments being only partially shown.

Fig. 4 is a side elevational view of the barrel ejecting device detached from the scrubber.

Fig. 5 is a part sectional, part elevational view of one of the brushes for scrubbing one of the ends of a barrel, and which view includes the means for mounting the brush for rotation and for reciprocation.

Fig. 6 is an end elevational view of the body brush and frame supporting the same, the scrubber compartment walls being indicated in section. This brush is for scrubbing the body of the barrel.

In detail the invention as illustrated (Figs. 2, 3) may generally comprise a washer or soaker 1 through which the barrels are conducted in a row to a scrubber 2. The scrubbing of the heads or ends of the barrels and the sides by brushes occurs in the scrubber, and after this step is completed the barrels are delivered to the rinser for passage therethrough.

The washer or soaker 1 may be provided with any suitable piping, spray nozzles, etc. (not shown) for washing the barrels with whatever medium is found to be most desirable for effecting

the cleaning. The rinser 3 may also be provided with any desirable type of rinsing equipment. The present invention is not particularly concerned with the piping and solutions or liquid used in the soaking, washing or rinsing operations.

The barrels 4 (dot-dash line in Fig. 3) may be of the usual drum type or of the type having convex sides and are adapted to be supported in the washer 1 in a row on their sides for rolling on spaced horizontal tracks or strips 5 extending longitudinally of such row. These tracks 5 may be carried in any suitable manner in the washer spaced above the floor of the latter and the barrels are rolled along said tracks to the scrubber by means of spaced cross bars 7 carried at their ends by endless chains 8. A pair of sprockets at each end of the washer support the chains, the pair adjacent said washer being indicated at 9 and being secured on shaft 10. Each bar 7 may carry spaced rollers or disks 11 therein for engaging barrels of the usual barrel shape having convex sides rather than barrels of the drum type, said rollers being equally applicable for both types however, and they function to assist in centering the barrels in the washer on tracks 5. Leaf springs secured at one of their ends to the sides of the washer and extending at their opposite ends 13 (Fig. 2) toward each other will also facilitate centering the barrels on tracks 5 before they enter the scrubber.

The scrubber 2 has lateral sides and a bottom. One of said sides opens into the washer and the side opposite thereto opens into the rinser, while a drain 14 opens outwardly from the bottom portion of the scrubber.

Within said scrubber and extending transversely thereacross and transversely relative to the washer and rinser are a pair of horizontal spaced rotatably supported shafts 15, 16 respectively provided with a pair of spaced rollers 17 thereon. The rollers of said pairs are equally spaced apart and the rollers of each pair are flanged at 18 at their opposite outer sides (Fig. 2). This arrangement provides for supporting a barrel on rollers 17 with the flanges 18 outwardly of the opposite outer ends of the barrel so as to prevent excessive undesirable longitudinal shifting of such barrel.

The shaft 15 carries a pinion 20 at one end outside the scrubber housing (Fig. 2). Pinion 20 is in mesh with a gear 21 on a rotatably supported shaft 22. A pinion 23 on said shaft 22 is in mesh with a gear 24 on a shaft 25. This latter shaft 25 carries a pair of sprockets 26 secured

thereto. One of said sprockets 26 connects with a drive sprocket 27 on shaft 10 by a chain 28 while the other sprocket 26 connects by a chain 29 with a sprocket 30 on a shaft 31 which latter shaft constitutes a drive shaft in the rinser 3 for a conveyor means that is identical with that in the washer except that it moves the barrels away from the scrubber.

The opposite end of shaft 15 carries a sprocket 33 that is connected by a chain 34 with a sprocket 35. The latter is secured on a rotatably supported shaft 36. Shaft 36 carries a pulley 38 that in turn is connected by a belt 39 with a pulley 40 secured to the drive shaft 41 of a motor 42.

The chain 34 also connects sprocket 33 with a sprocket 43 that is secured on one end of shaft 16. Thus motor 42 will drive shafts 15, 16 in the same direction for rotating a barrel or drum 4 supported on rollers 17. At the same time the said motor will drive the conveyor devices in the washer and in the rinser in a manner for moving barrels from the washer to the scrubber and then away from the scrubber through the rinser.

A pair of end brushes 44 face toward each other within the scrubber adjacent opposite side walls 45, 46 thereof. These brushes are spaced apart for receiving between them one of the barrels 4 with the heads of the barrels or drums adjacent the brushes respectively. Brushes 44 are secured on the adjacent ends of aligned shafts 47 that rotatably extend through the said side walls 45, 46, and which shafts are each rotatable and reciprocable in a bearing 48 outside each of said side walls (Fig. 5).

One shaft 47 reciprocably extends through a hollow shaft 49 and the other shaft similarly extends through a similar shaft 50. The shaft 49 extends between bearings 48, 51 while shaft 50 extends between bearings 48, 52 and which bearings prevent longitudinal movement of shafts 49, 50. Each shaft 47 is splined to the hollow shaft 49 or 50 through which it extends as best indicated in Fig. 5. Thus rotation of the shafts 49, 50 will effect rotation of the brushes 44 and at the same time said brushes may be moved toward and away from each other.

The outer ends of shafts 47 are each connected with the piston rod 54 of a piston or plunger 55 in a cylinder 56 secured to a stationary support 57 (Fig. 5). A spring 58 in each cylinder functions to move the piston toward the outer end of each cylinder and to thereby move the brushes 44 in direction away from each other, but upon admission of compressed air to within the outer end of each cylinder the pistons and brushes are moved in a direction toward each other for engagement between the brushes and the heads of a barrel or drum that is on rollers 17, as will later be described more in detail.

A sprocket 59 on hollow shaft 49 is engaged by sprocket chain 34, and a chain tightener wheel 60 positioned between sprockets 43, 59 functions to hold said chain taut and in driving engagement with sprocket 59.

A sprocket 61 on shaft 50 is connected by a sprocket chain 62 with a sprocket 63 that is secured on the end of shaft 16 that is opposite the sprocket 43. Thus the brush 44 that is connected with shaft 50 for rotation therewith will be driven upon rotation of shaft 16 (Fig. 2). A chain tightener 64 is also employed with chain 62.

A covered frame 65 extends across the upper end of the scrubber compartment in which brushes 44 and rollers 17 are positioned. This

frame is pivoted at the end nearest the washer 1 on a horizontal shaft 66 that is carried by wall 67 of the scrubber adjacent said washer 1. Thus the opposite end of the frame may swing up and down.

An elongated, horizontally extending body brush 68 supported on a shaft 69 is below said frame 65 and parallel with shaft 66. The shaft 69 is rotatably supported at its ends in suitable bearings 70 that are secured to said frame and one end of said shaft extends through an arcuate slot 71 in wall 46. The end of said shaft projecting outwardly from said slot carries a pulley 72. The pulley 72 is connected by belt 73 with a pulley 74 that is connected with the drive shaft of motor 75. The motor 75 is supported on the upper side of frame 65 for swinging with the latter. The brush 68 is positioned for swinging into and out of engagement with one side of the barrel or drum 4 that is supported on rollers 17, and said brush is preferably slightly offset in direction toward the rinser with respect to a vertical plane longitudinally bisecting a drum 4 that is on said rollers 17, as best seen in Fig. 3. From the foregoing it will also be seen that the brush 68 is driven independently of the brushes 44 and of any other part of the apparatus.

The outer end of frame 65 which is that end opposite shaft 66, is suspended from one of the ends of a pair of sprocket chains 80, and which chains extend over a pair of sprockets 81 (Fig. 3) secured to the scrubber frame in any suitable manner. The opposite ends of said chains 80 carry counterweights 83. These counterweights 35 are not sufficiently heavy to hold the outer end of frame 65 elevated, but merely assist other power means for swinging said frame upwardly when a scrubbing operation on a barrel 4 is completed so as to permit removal of the barrel. In 40 operation the weight of the frame 65, brush 68, motor 75, etc. is sufficient to hold the brush 68 in scrubbing relation to a barrel 4. Said sprockets 81 are secured on a shaft 84 that is rotatably supported in suitable bearings on frame 82 45 (Fig. 3).

One end of said shaft 84 carries a sprocket 85 (Figs. 1, 3) over which extends a chain 86 and to which sprocket one end of said chain is secured. The opposite end of chain 86 connects 50 with the piston rod 87 of a piston that is reciprocable in an air cylinder 88. Upon introduction of compressed air into the end of cylinder 88 that is nearest sprocket 85, it will be seen that shaft 84 will be rotated in a direction for raising the 55 outer end of the frame 65 and the brush 68 will be elevated so as to permit removal of a barrel 4 from rollers 17. The cylinder 88 is stationarily secured on the scrubber frame by any suitable means such as bracket 89.

Below the shaft 16 that is nearest the rinser, and parallel with said shaft is a rotatably supported shaft 90 that extends through the scrubber compartment. This shaft 90 has a pair of arms 91 secured thereto, and which arms extend 65 under the ends of a barrel or of a drum 4 that is adapted to be supported on rollers 17. The outer end portions 93 of said arms extend arcuately upwardly (Fig. 4) and portions 94 extend arcuately downwardly from the portions 93. The 70 convex edges of said portions 94 face toward the washer 1 and function to hold an oncoming barrel 4 from interfering with the removal of a barrel on rollers 17 while arms 91 and their end portions 93 are moved upwardly to roll a barrel 75 from rollers 17 to rinser 3.

On one end of shaft 90 and outwardly of side 45 of the scrubber is secured one end of an arm 95. The opposite end of said arm is pivotally secured to the end of a piston rod 96 of a piston that is reciprocable within an air cylinder 97. Said cylinder 97 is in turn pivotally secured to a bracket 98 that is in its turn secured to wall 45 (Figs. 1, 3, 4).

Upon injection of compressed air into the end of cylinder 97 at the end thereof adjacent bracket 98 it will be seen that the arms 91 will be rocked for rolling a barrel 4 off rollers 17 and onto a downwardly inclined pair of track sections 99 (Fig. 3) in the rinser 3, and which track sections connect with tracks 100 in said rinser that correspond with tracks 5 in the washer.

Once each barrel is on tracks 100 the cross bars 101 of chains 102 that are on sprockets 103 on shaft 31 will move the barrels in spaced relation through the rinser. Rollers or disks 104 are on cross bars 101 the same as is provided for in the washer by rollers or disks 11. The shaft 31 is driven by chain 29 that extends over sprocket 30 on said shaft as has been previously described.

On shaft 31 is also a sprocket 106 that connects by a chain 107 with a sprocket 108 on shaft 109 of a timer located on top of the rinser adjacent the scrubber (Fig. 2, 3).

This shaft 109 has three cams 111, 112, 113 secured thereto and adjacent said cams are conventional lever type mercury switches 114, 115, 116 respectively, said switches each having its lever arranged for actuation by the cam adjacent thereto. Said switches are respectively in an electrical circuit in which are conventional solenoid actuated valves 117, 118, 119.

The cam 111, switch 114, and valve 117 are connected for actuation of the piston in air cylinder 97 that in turn actuates the arms 91 for ejecting a barrel from the scrubber into the rinser.

The cam 112, switch 115 and valve 118 are connected for actuation of the pistons in the cylinders 56, and which pistons are connected with the end brushes 44 for reciprocating the latter.

The cam 113, switch 116, and valve 119 are connected for actuation of the piston in cylinder 88, and which piston is connected with the frame 65 that carries the body brush 44 for lifting said brush through the chains 86, 80.

In operation the shaft 10 of the conveyor device in the washer is so synchronized with the cam 111 so that a barrel 4 will not be delivered from tracks 5 onto inclined tracks 120 (Fig. 3) for rolling toward the rollers 17 until the ejector arms 91 are elevated, and when so elevated, such barrel on tracks 120 will engage the convex edges of portions 94 of said arms. As soon as the arms 91 are lowered the barrel against portions 94 will automatically roll onto the rollers.

Also the delivery conveyor in the rinser is so synchronized with cam 111 that the barrel rolled off the rollers 17 will automatically roll between a pair of cross bars 101 of said delivery conveyor. The end brushes and the body brush are continuously rotating, as are the rollers 17, timer shaft 109 and conveyor shafts 10, 31.

With the above explanation a cycle of operation will be explained, assuming that a barrel 4 has been delivered onto rollers 17 and the end brushes and body brush are in operation as seen in Fig. 1.

After the barrel or drum has been scrubbed for a predetermined time by the brushes, the cam 112 is first actuated so as to actuate valve 118 for closing the compressed air line 125 to the cylinders 56, thereby permitting the air behind the

pistons in said cylinders to be exhausted through lines 126 and exhaust 127 of valve 118 and to cause retraction of the brushes away from the ends of the drum. Cams 111 and 113 then function substantially simultaneously to respectively cause valves 117 and 119 to open to compressed air in line 125 through lines 128, 129 respectively connected with cylinders 97, 88. Thus the brush 68 will be raised and ejector arms 91 will be rocked thereby ejecting the barrel 4 onto the track sections leading to the rinser.

As cam 111 continues to rotate it relatively quickly moves to a position for actuating valve 117 for shutting off the air to cylinder 97 and permitting the air therein to exhaust through exhaust 130 or valve 117 whereby arms 91 will automatically be lowered, and a barrel 4 will automatically roll onto rollers 17. The cam 112 next functions to actuate valve 118 for admitting air into cylinders 56 for moving the rotating end brushes into engagement with the ends of the rotating drum, and finally the valve 119 is actuated by action of cam 113 for shutting off the air to cylinder 88 whereupon the body brush will be lowered by gravity onto the barrel and the air in cylinder 88 will be exhausted through exhaust 131 of valve 119. The cycle is then repeated.

The timing of the cams is entirely discretionary with the operator (but the operations are generally in order described) inasmuch as such timing may vary with the condition and sizes of the barrels. The particular setting of the cams in Fig. 1 is not therefore to be taken as critical or correct for all circumstances.

One of the important structural features in this invention is the positioning of the end brushes so that the axis of rotation of each brush is offset to one side of the axis of rotation of the barrel on rollers 17. The length of each brush is slightly greater than the radius of each barrel head. With each brush offset so that each brush will extend lengthwise from the rim of the barrel to past the center of each head it will be seen that every portion of the barrel head will be scrubbed thoroughly.

By the automatic means herein described for moving the barrels or drums from the inlet of the washer to the outlet of the rinser, and through the scrubber, the minimum of labor and time is required and this is very important inasmuch as the cost of cleaning the barrels or drums must in normal times be appreciably less than the cost of new barrels or drums.

The invention as hereinbefore described and as illustrated in the drawings is not to be considered restrictive of the invention, but merely illustrative of a preferred form thereof.

Having described the invention, I claim:

1. In a barrel washer, means for supporting a barrel on its side for rotation about its longitudinal axis and for so rotating said barrel, a rotary brush supported for rotation about an axis parallel with the aforesaid horizontal axis but offset to one side thereof, means supporting said brush for said rotation and for engagement with one end of said barrel during rotation of the latter, said brush being positioned to extend across the said axis of rotation of said barrel and to the sides of said barrel for scrubbing the entire exposed surface of said end upon one revolution of such barrel on its axis, said brush being movable axially of its axis of rotation toward and away from said barrel, pneumatically actuated means connected with said brush for so moving said brush axially thereof toward said barrel during

said rotation of said brush, valve and spring means associated with said pneumatically actuated means for respectively rendering the latter inoperative for so moving said brush toward said barrel and for moving said brush away from said barrel.

2. In a barrel washer, means for supporting a barrel on its side for rotation about its longitudinal axis and for so rotating said barrel, an elongated rotary brush extending axially of said axis and rotatable about its axis, means supporting said brush for said rotation and for movement laterally of said barrel into and out of engagement with a side thereof during rotation of said barrel and of said brush, the said means supporting said brush for said rotation thereof and for said movement laterally of said barrel comprising a generally horizontal frame pivoted at one end for swinging of its opposite end vertically toward and away from said barrel, said brush being rotatably carried on said opposite end.

3. In a barrel washer, means for supporting a barrel on its side for rotation about its longitudinal axis and for so rotating said barrel, an elongated rotary brush extending axially of said axis and rotatable about its axis, means supporting said brush for said rotation and for movement into and out of engagement with a side of said barrel offset to one side of a vertical plane parallel with the axis of said barrel and bisecting the latter during rotation of said barrel and of said brush, the said means supporting said brush for rotation thereof and for said movement laterally of said barrel comprising a generally horizontally disposed frame pivoted at one end for swinging of the opposite end by gravity about a horizontal axis downwardly toward said barrel, said brush being rotatably carried on said opposite end, power means for moving said opposite end of said frame including said brush upwardly from said brush, and a counterweight connected with said frame for facilitating actuation of said last mentioned means.

4. A barrel washer of the character described comprising rotary power driven means for supporting a barrel on its side for rotation about its axis, a pair of end brushes adjacent opposite ends of such barrel facing such ends and respectively supported for rotation about an axis parallel with the said axis of said barrel but offset to one side thereof, means for so rotating said end brushes, means for moving said end brushes into and out of engagement with the said ends of such barrel, a horizontally extending rotary body brush supported for movement into and out of engagement with one side of a barrel when such barrel is on said power driven means, means for rotating said body brush about its longitudinal axis, barrel moving means for removing a barrel adapted to be supported on said power driven means therefrom, means operatively connecting the said means for moving said end brushes and the said means for moving said body brush and the said barrel moving means for automatic actuation of the former two means for moving said end and body brush toward and away from a barrel adapted to be supported on said power driven means and for moving said barrel moving means to remove such barrel in the interval when said end brushes and said body brush are moved away from such barrel, and automatically actuated means for delivering a barrel onto said power driven means immediately upon such removal of a barrel therefrom.

5. In a barrel washer, means for supporting a barrel on its side for rotation about its longitudinal axis and for so rotating said barrel, a pair of horizontally opposed rotary brushes positioned to engage opposite ends of such barrel, the axes of said brushes being parallel and offset to one side of said longitudinal axis of said barrel, means for simultaneously rotating said brushes, and means for yieldably urging said brushes against said ends of such barrel during rotation of the latter and during rotation of said brushes, a horizontally extending rotary brush disposed above such barrel extending the full length of the latter, a motor connected with said brush for rotating the same, means swingingly supporting said brush and motor for generally vertical movement of said brush against said barrel under the influence of the weight of said brush and motor, whereby said brush will be yieldably in engagement with said barrel during rotation of the latter and of said brush, and fluid actuated means for lifting said brush out of engagement with said barrel.

6. In a barrel washer, horizontally disposed rollers for supporting a barrel at its opposite end portion thereof with its axis horizontal for rotation of the barrel about its said axis, said rollers being positioned for engaging the lower side of said barrel adjacent its ends, and flanges on said rollers extending over the end edges of said barrel for preventing longitudinal movement of the latter, means for rotating said rollers in one direction for rotating a barrel thereon, rotary brushes positioned to engage opposite ends of said barrel, the axes of said brushes being parallel with the axis of said barrel, means for rotating said brushes on their said axes, pneumatically urged pistons connected with said brushes and respectively coaxial therewith for yieldably urging said brushes into engagement with the said ends of said barrel during rotation of the barrel and brushes.

7. In a barrel washer, horizontally disposed rollers for supporting a barrel at its opposite end portion thereof with its axis horizontal for rotation of the barrel about its said axis, said rollers being positioned for engaging the lower side of said barrel adjacent its ends, and flanges on said rollers extending over the end edges of said barrel for preventing longitudinal movement of the latter, means for rotating said rollers in one direction for rotating a barrel thereon, rotary brushes positioned to engage opposite ends of said barrel, the axes of said brushes being parallel with the axis of said barrel, means for rotating said brushes on their said axes, pneumatically urged pistons connected with said brushes and respectively coaxial therewith for yieldably urging said brushes into engagement with the said ends of said barrel during rotation of the barrel and brushes, yieldable means for guiding barrels onto said rollers, and spring means for withdrawing said brushes from engagement with the opposite ends of said barrels.

8. In a barrel washer, supporting means for supporting a barrel on its side for rotation about its horizontal axis and for so rotating such barrel, a pair of rotary end brushes supported outwardly of opposite ends of said barrel for reciprocation into and out of engagement with said ends, means for rotating said end brushes during said rotation of said barrel, a body brush positioned to engage the upper side of said barrel from end to end thereof during rotation of the

barrel, ejector means for ejecting a barrel from said supporting means after the barrel has been scrubbed by said brushes, means for yieldably urging said end brushes into engagement with said ends during rotation of said barrel and 5 brushes, means for revolving said body brush, pneumatically actuated means for yieldably urging said end brushes into engagement with the ends of the barrel during rotation of the latter and for elevating said body brush to said elevated 10 position and for actuating said ejector means for ejecting said barrel, means for yieldably urging said body brush into engagement with a side of said barrel and means for moving said end brushes to retracted position, feed means for automatically feeding a barrel onto said rollers after each actuation of said ejector means, and control means for automatically controlling the movement of said body and said end brushes into and out of engagement with a barrel on said rollers 15 and for controlling the actuation of said ejector means for repeating the scrubbing and ejection of barrels fed onto said rollers from said feed means.
